UNITED STATES PATENT OFFICE.

PAUL F. WILLIAMS, OF CHICAGO, ILLINOIS, ASSIGNOR TO G & W ELECTRIC SPECIALTY CO., OF CHICAGO, ILLINOIS, A CORPORATION OF ILLINOIS.

CONNECTOR FOR ELECTRICAL CONDUCTORS.

1,228,156.

Specification of Letters Patent.

Patented May 29, 1917.

Application filed March 17, 1913. Serial No. 754,726.

To all whom it may concern:

Be it known that I, PAUL F. WILLIAMS, a citizen of the United States, residing at Chicago, in the county of Cook and State of Illinois, have invented a certain new and useful Improvement in Connectors for Electrical Conductors, of which the following is a full, clear, concise, and exact description, reference being had to the accompanying 10 drawings, forming a part of this specification.

My invention relates to devices for terminating and connecting electrical conductors, and especially to a type of device involving a 15 tubular or hollow casing or housing for an end portion of one of the conductors to be terminated or connected. In my Patent No. 831,815, issued to me September 25, 1906, I show a connector for electrical conductors, 20 involving a hollow or tubular casing, in which one end of a cable is terminated and also involving a cover for said casing and connecting devices for the conductors.

Prominent objects of my present invention 25 are to provide a simple, practical and effective device of the class specified; to arrange for the proper termination and connection of the conductors and also to permit effective insulating of the same; to simplify and 30 cheapen the cost of manufacture; and to secure the foregoing and other desirable results in a simple and expeditious manner.

In the accompanying drawings Figure 1 is an elevation of a multiple conductor device 35 involving my present invention;

Fig. 2 is a plan view of the same;

Fig. 3 is a view in longitudinal section of a single conductor device involving certain features of construction disclosed in the 40 multiple conductor device of Fig. 1, but modified with respect thereto in certain respects;

Fig. 4 is a view similar to Fig. 3 of another modification; and

45 Figs. 5, 6, 7 and 8 are views of the upper end portions of still other modified forms.

Referring first to Fig. 1, I show a case 1, preferably made with a straight vertical side 2, and a bulging or projecting side 3 opposite the side 2. Both the sides 2 and 3 are 50 preferably semi-circular in cross section, or in other words semi-cylindrical in form, as shown in Fig. 2. The side 2 is provided with upper and lower cross pieces 4 and 5

adapted to form connecting supports for the 55 attachment of the device. The front and back walls 6 and 7 are preferably straight as shown in Fig. 2, whereby there is formed the irregular shaped structure possessing the peculiarities above referred to. The bottom 8 of the casing is provided with an aperture 60 preferably circular in form so as to admit a cable 9, which cable or the strands thereof are to be terminated or connected. The top 65 of the casing is provided with a lid or cover 10, preferably having small over-hangs 11, so that the cover is adapted to fit snugly upon and over the upper end of the casing 1. Several tubular members 12—12 are mounted upon and rise from the lid or cover 10. 70 Three of these members 12 are shown but the number, of course, could be varied, there being three in the present instance because there are three strands in the cable 9, and a member 12 is provided for each one of said 75 strands. These members 12 are preferably made in a straight row from side to side of the device. Each member 12 is preferably in the form of a hollow cylindric device with its 80 sides provided with corrugations 13, and its lower end is provided with an aperture capable of receiving a cable strand with more or less of the insulation upon it. The connection between each member 12 and the lid or cover 10 is effected by means of a hollow 85 projection 15 preferably made integral with the lid 10, and extending up in somewhat conical form above the surface of said lid, as well shown in Fig. 1. These projections 15 conveniently fit against the lower ends of 90 the corrugations 13 so as to support and hold the members 12 in proper position, and insulating material 16 is desirably arranged within hollow annular spaces in said members 15. The lid or cover 10 is desirably 95 held in place by bolts 17—17 adapted to engage lugs 18—18 on the lid 10 and also lugs 19—19 on the body member or casing 1, as an alternative arrangement, screws 20—20 passing through the cover into the sides of 100 the casing 1 may serve to hold the cover in place.

Each member 12 is provided with a cover or cap 21 which fits over and covers the open upper end of said member 12. The cable strand 22 although provided with insulation where it enters the bottom 14 of the member 12 is stripped of its insulation 105

so that the bare conductor 23 is exposed within the member 12 and extends up through an aperture in the top of the cap 21. A sleeve 24 is fitted over said exposed or 5 bare conductor, said sleeve 24 extending substantially the length of the top or cap 21 and having its lower end projecting into the chamber 25 of the member 12 at which point it is engaged by screws 26-26 passing 10 through the upper end portion of the member 12 and into opposite sides of the lower end portion of the sleeve 24. The upper end of the sleeve 24 is preferably screw threaded, as at 27, and a cap piece 28 having a 15 threaded bore is fitted upon the upper end of the top 21 and screwed into engagement with the threaded portion 27 of the sleeve 24. The sides 29 of the cap piece 28 are extended down and fitted upon the upper end 20 portion of the conical exterior of the top 21, whereby the cap piece 28 with its downwardly extending lips 29 forms a water tight protection and cover for the upper end of the top 2. The cap piece 28 is preferably 25 made of metal and the top 21 and tubular member 12 are preferably made of insulating material such as porcelain. A gasket 30 is desirably interposed between the cap piece 28 and the upper edge of top 21, and 30 another gasket 31 is desirably interposed between the lower edge of the top 21 and upper edge of the uppermost corrugation 13. Thus it will be seen that a cable strand is led into the lower end of casing 1 and 35 then through the same to one of the members 12 with the insulation on said strand within the bowl or casing 1, but removed from the same in the interior of the tubular member 12, and that the bared or exposed 40 conductor is terminated and connected with by means of the sleeve 24 which is soldered or otherwise secured to the conductor. Screws 26 pass through said sleeve and if desired engage the conductor so as to hold 45 the same in proper position. It will be understood that insulating material or compound is preferably introduced within the chamber 25 of the member 12 and thus it will be seen that such insulating material 50 or compound can be put into the interior of the member 12 after the cable strand is drawn up and placed and fastened in proper position in the same by the screws 26. Thus the cable strand or conductor can be prop- 55 erly fixed in place and then the insulating compound put inside the member 12 and then after this the top 21 can be put in place, thus permitting the connection to be very conveniently made. After the top 21 is in 60 place the cap piece 28 can be put on the sleeve 24 and screwed down into position against the cover 21. In this way a thoroughly water tight structure is made. The interior of only one of the tubular members 65 12 is shown in Fig. 1, but it is understood

that the interiors of the other two members 12-12 shown, may be the same, affording terminal connection for the other two strands of the cable 9, which strands it will be seen are distributed and extended to the proper tubular members within the interior of the bowl or casing 1, the arrangement thus permitting the bowl or casing to be secured to a straight wall on one side and the cable run up alongside of that wall, and then 70 the strands of the cable being distributed to outlet structures which are arranged one after the other away from the wall. Insulating material or compound may be arranged within the interior of the bowl or casing 1 by means of holes in the lid closed with pipe plugs 10^a-10^a, if desired. The cable sheath is preferably terminated at the bottom of the bowl or casing 1 whereby the insulating material within such bowl or casing serves to insulate further the unsheathed cable strands. The lower end of the bowl or casing 1 is made in the form of a tapering tube 33, extending down along the cable sheath and a wiped joint 34 is desirably 80 made connecting the tube or sleeve-like member 33 with the cable 9. 85

In Fig. 3 I have shown an outlet structure of the general type or character of the outlet arrangements of the device of Figs. 1 and 2, the device of Fig. 3 showing such outlet structure somewhat modified and forming an individual single conductor device by itself. The arrangement of Fig. 3 comprises the tubular member 12 with 90 cover or top 21 and other parts the same, except that the bared cable conductor 23^a (Fig. 3), does not extend clear through the top 21 as the conductor 23 of Fig. 1 does. But on the contrary the cable conductor 23 is terminated within the member 12 and fitted into a socket at the lower end of a connecting device 35 which is conveniently 95 in the form of a metal cylindric structure having sockets in its opposite ends, one of which as stated receives the end 23^a of the cable conductor, and the other of which receives the end 36 of a conductor to be connected with the cable conductor 23^a. The connecting piece 35 is extended through the 100 top or cover 21, and is held in place by being fastened to the upper end of the member 12 by screws 26^a, which pass through the walls of said upper end of the member 12 into the lower end portion of the connector 35. The upper end of the member 35 is threaded at 38 and a metallic cap piece 28 is fitted and screwed upon the upper end of 35, said member being similar to the member 28 of Fig. 1, and provided with 110 downwardly extending lips 29. A gasket 39 is conveniently interposed between the top 21 and upper end of member 12. By 115 this arrangement the cable conductor 23^a can be led into the member 12 and secured 120 125 130

in the proper position therein by screws 26^a, and then compound can be filled into the interior of the member 12 and then the top 21 put in position and then the cap 28 screwed down and then the conductor 36 fitted into the upper end of the member 35. This allows connection to be made between two different conductors and also gives the advantage of allowing the compound to be 5 filled into the interior of the member 12 before the top 21 is put in place. As an arrangement for supporting the member 12 I show in this Fig. 3 a shell 40 preferably of metal as brass, adapted to inclose the 10 lower end portion of the member 12 and fit against the lower corrugation 13 thereof, said shell 40 having a projection 41 coöperating with a clamp 42 adapted to clamp a piping 43 or other device on which the arrangement is to be supported. The lower 15 end of the shell 40 is provided with a tapering tubular projection 44 which extends down along the exterior of the cable sheath 45, and is connected with the same by a 20 wiped joint 46.

Referring to Fig. 4, I have shown an individual device involving a disconnecting arrangement. The body part 12 contains a socket member 47, into the lower end of 25 which the bared end 23^b of the cable conductor is inserted. This member 47 has a socket 48 into which a plug member 49 is introduced and held by screws 26^b—26^b, passing through the upper end of the insulating tube or member 12. The plug member 49 is hollow or cylindrical having a 30 collar 50 at its upper end fitting against the upper end of the socket member 47. A plug connecting device 51 has a reduced end portion 52 which fits into the member 49, the upper end of said member 51 being extended through and fitted into the top 21^a, said member 51 also having its upper end 35 53 extended laterally so as to cover the opening at the top of 21^a, and also having an overhang 54 extending part way down the sides of the top 21^a. The lower end of the member 12 is fitted into a shell 40^a, which has an extension 55 forming a stuffing 40 box having a screw threaded plug 56 which receives and fits closely about the cable sheath 45, waste or stuffing material 57 being confined within the chamber formed by the extension 55. The top 21^a 45 has a petticoat 58.

Referring to Fig. 5, this figure shows simply the upper end of a device, the lower portion of which may be of any desired construction, as for example as shown in Fig. 60 3, or Fig. 4. In this device of Fig. 5 the top 21 is shown containing the bared conductor 23 which is understood to run through the device, as shown in Fig. 1. A cap member 28 similar to the same member 65 of Fig. 1 incloses a threaded sleeve 24^a,

which is secured into the cap 28. A small set screw 60 is passed through the sleeve 24^a, and into the conductor 23, thus making firm connection between said conductor and said sleeve.

Referring to Fig. 6, which is a view of only the upper part of a device, as in Fig. 5, the top 21 is shown inclosing a connecting member 61, whose upper end 62 is screw threaded and projects up above the upper 70 end of the top 21. A cap member 28^a having an overhang 29^a is secured upon the top of the member 62, a common rubber or insulating gasket 63 being preferably interposed between the member 28^a and top 21. 75 The member 28^a is provided with a projection 64 having an aperture 65 to which projection by way of the aperture 65 connection can be made by another conductor 80 which is to be connected with the member 85 61.

Referring to Fig. 7 which is a figure similar to Figs. 5 and 6, I show the top 21 surrounding a member 62 similar to the member 62 of Fig. 6 and caps 28^b and 28^c secured 90 upon the projecting end of the member 62. The cap 28^c has an overhang 29. A connecting device 66 having an opening to receive the upper end of the member 62 is interposed between the caps 28^b and 28^c and 95 the cap 28^b is screwed down upon said member 66 so as to make a tight connection therewith. The member 66 has an aperture 67 by which connection can be made.

Referring to Fig. 8, this figure shows a 100 closure 70 preferably in the form of a plate having a threaded connection with the interior member 71 which may be a connecting device or other element, the plate 70 being when screwed down fitted against the upper 105 edges of the tubular member 12. By this arrangement the tubular member 12 may be continually closed to prevent the compound from running or flowing out if the device is laid upon its side or inverted. 110

It will be understood that changes can be made without departing from the spirit of the invention.

What I claim is:

1. A device of the class specified comprising in combination, a tubular outlet, a cover for the same, a connecting device extending through said cover and having its lower end projecting into the upper end of said tubular member, means for securing 115 the lower end of said connecting device to the upper end of said tubular member, and a cap fitting over the upper end of said cover.

2. In a device of the class specified, a 120 tubular outlet member containing a connecting device, screws extending through the walls of the outlet member to the connecting device and making connection with the latter, and a top extending down over the 125 130

- upper end of said outlet member and covering the ends of said screws.
3. In a device of the class specified, a tubular outlet member containing a connecting device, securing means extending crosswise through the outlet member and engaging the connecting device, a cover for the outlet member, said connecting device extending up through said cover and a cap member fitted over the upper end of said cover.
4. In a device of the class specified, a tubular outlet member containing a connecting device, securing means extending crosswise through the outlet member and engaging the connecting device, a cover for the outlet member, said connecting device extending up through said cover and a cap member fitted over the upper end of said cover, and surrounding the upper end portion of said connecting device.
5. In a device of the class specified, a tubular insulator forming an outlet member, a removable cover of insulating material fitted over the upper end of said insulator, a metallic connecting device confined within said cover and having its lower end projecting into the insulator and its upper end projecting above the upper end of the cover, securing means extending crosswise of the insulator near the upper end thereof and from the wall of the same to the connecting device for holding the lower end of the latter in position, and a metallic cap fitted over the upper end of the cover and engaging the upper end portion of said connecting device.
6. In a device of the class specified, a tubular insulator forming an outlet member, a removable cover fitted over the upper end of said insulator, a metallic connecting device confined within said cover and having its lower end projecting into the insulator and its upper end projecting above the upper end of the cover, securing means extending crosswise of the insulator and from the wall of the same to the connecting device for holding the latter in position, and a metallic cap fitted over the upper end of the cover and surrounding the upper end portion of said connecting device, there being a screw threaded connection between said cap and the upper end of said connecting device.
7. In a device of the class specified, a tubular insulating member forming an outlet, an insulating cover for the same, a connecting device in the form of a metallic sleeve arranged within said cover and having its lower end projecting into the upper end of the insulator and its upper end projecting above the top of said cover, screws extending through the walls of the insulator and engaging the metallic sleeve and a metallic cap having a screw threaded connection with the upper end of said sleeve and having an overhang extending down the upper side portion of the cover.
8. In a device of the class specified, a tubular insulator forming an outlet, an insulating cover for the same, a connecting device arranged within said cover and having its lower end projecting into the upper end of the insulator, and having its upper end projecting above the top of the cover, said connecting device having sockets at its opposite ends, screws extending through the walls of the upper end portion of the tubular insulator, and into the lower end portion of said connecting device, the lower end of the cover extending down over and covering the outer ends of said screws, and a metallic cap piece fitted over the upper end of the cover and having a screw threaded connection with the upper end of said connecting device.
9. In a device of the class specified, the combination of an insulating outlet member and a cover therefor, a connecting device extended through the cover from top to bottom thereof, means for engaging the connecting device and upper end of the cover, and means for securing the lower end of the connecting device to the insulator.
10. A device of the class specified comprising a tubular outlet member, a cover for the same, a connecting device extending through said cover into the upper end of said outlet member, and means for securing the lower end of said connecting device to the upper end of said outlet member.
11. A device of the class specified, having a cover containing a sleeve and a set screw passing through said sleeve to engage a conductor within the same, in combination with a metallic cap having a screw threaded connection with said sleeve and forming a protector for the upper end of said cover.
12. A device of the class specified comprising a tubular outlet member, a cover for the same, a connecting device extending through said cover into the upper end of said outlet member, means for securing the lower end of said connecting device to the upper end of said outlet member, and a cap mounted upon the upper end of said cover and detachably connected with the upper end of said connecting device.
13. A device of the class specified comprising a tubular outlet member made of insulating material, a cover adapted to fit removably over the top of said outlet member and also made of insulating material, a connecting device extending through said cover from top to bottom thereof, the lower end of said connecting device projecting into the upper end of said outlet member and being smaller than the same so as to leave a space between the lower end of said connecting device and the interior side walls

of the upper end of said outlet member, means extending crosswise to the upper end of said outlet member to the lower end of said connecting device and holding the same in position, and a metallic cap mounted upon the upper end of said cover and detachably connected with the upper end of said connecting device.

14. A device of the class specified comprising a tubular outlet member made of insulating material, a cover adapted to fit removably over the top of said outlet member and also made of insulating material, a connecting device extending through said cover from top to bottom thereof, the lower end of said connecting device projecting into the upper end of said outlet member and being smaller than the same so as to leave a space between the lower end of said connecting device and the interior side walls of the upper end of said outlet member, means extending crosswise to the upper end of said outlet member to the lower end of said connecting device and holding the same in position, a metallic cap mounted upon the upper end of said cover and detachably connected with the upper end of said connect-

ing device, and insulating cement substantially filling the interior of said tubular outlet member.

15. The combination with a tubular insulating member and a cover therefor, of a connecting device within the tubular member and a closure for the open end of the tubular member, said closure being located within the cover and having an aperture through which said connecting device passes.

16. The combination with a tubular member and cover therefor, of a connecting device within the tubular member and a closure for the open end of the tubular member comprising a plate located within the cover and having a threaded connection, with the connecting device and fitting against the upper edges of the tubular member.

In witness whereof, I hereunto subscribe my name this 10th day of March, A. D., 1913.

PAUL F. WILLIAMS.
